TRANSFORMER LEARNING CENTER

Daniel M. Flynn, Hampden, Stanley J. Bandoski, Jr.,
Springfield, and William R. Clow, Agawam, Mass., as-
signors to Hampden Engineering Company, East Long-
meadow, Mass.

Filed July 28, 1970, Ser. No. 24,177

Term of patent 14 years

Int. Cl. D19—07

U.S. Cl. D25—1

Fig. 2A

Fig. 2B

Fig. 2C

FIGS. 1A and 1B respectively illustrate upper and lower portions of the transformer learning center in front elevation.

FIGS. 2A, 2B and 2C respectively illustrate upper left, upper center and upper right-hand portions of the transformer learning center in enlarged fragmentary front elevation, the said portion being difficult to reproduce in detail in a smaller scale.

FIG. 3 is a top view of the transformer learning center.

FIG. 4 is a left-hand end elevation of the transformer learning center, with various detailed elements and indicia on the lower portion omitted due to their illegibility in extremely small scale.

FIG. 5 is a front elevational view with various detailed elements and indicia of FIGS. 1A and 1B omitted due to their illegibility in extremely small scale.

FIG. 6 is a right-hand end elevation of the transformer

FIG. 7 is a fragmentary enlarged left-hand end elevation showing a lower portion of the transformer learning center and including elements and indicia omitted in FIG. 4.

FIG. 8 is a rear elevational view of the transformer learning center.

FIG. 9 is a bottom view of the transformer learning center.

We claim:

The ornamental design for a transformer learning center, as shown and described.
